(57) **CLAIM**

The ornamental design cover for a deodorant cabinet, as shown and described.

DESCRIPTION

FIG. 1 is a perspective view showing of top, right side and front of a cover for a deodorant cabinet according to one embodiment of my new design;

FIG. 2 is a perspective view showing the bottom, left side and front of the cover shown in FIG. 1;

FIG. 3 is an enlarged front view of the cover shown in FIG. 1;

FIG. 4 is a greatly enlarged right side view of the cover shown in FIG. 1, the opposite side being a mirror image of that shown;

FIG. 5 is a bottom view of the cover shown in FIG. 1;

FIG. 6 is a top view of the cover shown in Figure;

FIG. 7 is a perspective view showing the top, left side and front of a cover for a deodorant cabinet according to a second embodiment of my design; and,

FIG. 8 is a perspective view bottom, right side and front of the cover shown in FIG. 7.
